MACHINE FOR TRANSFER PRINTING ON
CIRCULAR OBJECTS

Vincent J. Tenety, Jersey City, N. J.; Helen M. Tenety executrix of said Vincent J. Tenety, deceased

Application December 31, 1949, Serial No. 136,268

16 Claims. (Cl. 101—38)

1

This is a new and improved machine for transfer printing on objects of roughly circular section concentric with a single axis. Examples of such objects are vases, jars, and bottles of round or substantially round horizontal section. The invention will be fully understood from the following description read in conjunction with the drawings in which:

Fig. 1 is a plan view of the machine;

Fig. 2 is a plan view of the machine with certain parts omitted and in a different operative position;

Fig. 3 is a side view of the machine;

Fig. 4 is a view of the showing in Fig. 3 on the plane indicated by 4—4;

Fig. 5 is a view of the showing in Fig. 3 on the plane indicated by 5—5;

Fig. 6 is a plan view of a fragment of the showing in Fig. 1;

Fig. 7 is a view of the showing in Fig. 6 on the plane indicated by 7—7;

Fig. 8 is a detail of a fragment of the showing in Figs. 1 and 2;

Fig. 9 is a side view of one element of the showing in Figs. 4 and 5;

Fig. 10 is a detail of one element of the showing in Fig. 3;

Fig. 11 is an end view of the showing in Fig. 10;

Fig. 12 is a section through Fig. 1 on the plane indicated by 12—12;

Fig. 13 is a detail of one element of the showing in Figs. 1, 2, 4 and 5;

Fig. 14 is a section through part of the construction shown in Fig. 2 on the plane indicated by 14—14;

Fig. 15 is a view of part of the construction shown in Fig. 2 on the plane indicated by 15—15;

Fig. 16 is a top view of the construction shown in Fig. 15;

Fig. 17 is a section through the construction shown in Fig. 15 on the plane indicated by 17—17;

Fig. 18 is a section through the construction shown in Fig. 15 on the plane indicated by 18—18;

Figs. 19 and 20 are details of the construction shown in Fig. 16;

Fig. 21 is a detail of a fragment of Fig. 3 on the plane indicated by 21—21;

Fig. 22 is a detail of a fragment of the showing in Fig. 3 on the plane indicated by 22—22 with intervening parts removed to show cam contours; and

2

Fig. 23 is a detail of one element of the showing in Figs. 4 and 5.

Referring to the drawings the machine comprises angle iron legs 1, 2, 3 and 4 (Figs. 3, 4 and 5) stiffened by longitudinal angle iron braces of which 5, 6 and 7 appear in Fig. 3 and symmetrically disposed braces on the opposite side (not shown) and stiffened also by transverse angle iron braces of which 8 and 9 appear in Fig. 4 and 10 and 11 appear in Fig. 5. The table also includes floor 12 (Figs. 3, 4 and 5) resting on brace 5 and its corresponding brace on the opposite side. These parts collectively constitute a table or platform 13. Mounted on and extending upwardly from the table or platform are the channel rails 14 and 15 and the angle rail 16 (Figs. 4 and 5). Horizontal plate 17 is secured to the upper flanges of channel rails 14 and 15. As evident from the plan views (Figs. 1 and 2), the plate 17 does not occupy the entire area of the table 13 but, pro contra, is so formed as to leave a space on said table at either end and at the side of plate 17. Plate 17 may be hereinafter referred to as a bed plate. It is of substantial thickness and rigidity and bored throughout with evenly spaced vertical holes. The function of bed plate 17 is to support and carry impression plates 18, 19, 20, 21, 22 and 23, and the purpose of the vertical holes (Fig. 6) in the bed plate is to facilitate the easy clamping of the impression plates in position by means of studs 24 and set screws 25 (Fig. 7).

Longitudinally extending metal strips 26 and 27 (Figs. 4 and 5) are secured to the outer edges of channel rail 14 and of angle rail 16. These strips 26 and 27 carry longitudinally extending racks 28 and 29 running the full length of platform 13 (Figs. 1-5).

31 (Figs. 1, 2 and 9) is a transversely extending offset roller, i. e., a transfer roller, the cylindrical surface of which is made up of a relatively soft and yielding material, such as the particular grade of rubber suited to offset printing. This roller is mounted on axle 32 splined at either end to spur gears 33 and 34 running in racks 28 and 29.

The impression plates 18, 19 and 20 (Figs. 1 and 2) are mounted in line on one side of bed plate 17. The impression plates 21, 22 and 23 are mounted in line on the other side of bed plate 17. These impression plates are ordinarily made by a photo-engraving process so that each impression plate carries in relief that part of the design to be printed which is to be reproduced in a selected color. The position of the impression

plates on the bed plate, the diameter of the offset roller 31 and the ratio of the gears 33 and 34 to the racks 28 and 29 is such that as the offset roller 31 rolls in succession over the three impression plates 18, 19 and 20, and similarly over the three impression plates 21, 22 and 23, it registers in turn with each of the three impression plates to pick up a composite three color image suitable for transfer by offset onto the article to be transfer-printed.

In the device as illustrated I have shown three impression plates for three color printing but it will be understood that I may, if desired, use only two color plates in succession for two color printing, or may alternatively, if desired, use any number of impression plates for the printing of a greater number of colors by suitably extending the length of bed plate 17 and of the cooperating racks 28 and 29. Within certain aspects of the invention I may use only a single impression plate for the transfer printing of a single color.

Inasmuch as the racks 28 and 29 extend the full length of table 13 and considerably beyond bed plate 17 (Figs. 1 and 2) it will be noted that offset roller 31 is capable of executing at least a complete turn at the end 35 of the device after rolling out of contact with the impression plate nearest end 35.

While within certain aspects of the invention the offset roller 31 may be manipulated by hand by means of the handles 36 and 37, in the preferred embodiment of my invention I provide means for mechanically operating the same. As illustrated in Figs. 3 and 5, this includes double acting air cylinder 38 operating piston 39, which air cylinder is rigidly secured to table 13. Piston 39 is connected to horizontally moving cross-head 42 slidably guided by the horizontally extending rod 43 (Fig. 3) secured at one end to vertical leg 1 of table 13 by fitting 44, and at the other end to vertical leg 2 of table 13 by fitting 45 (Fig. 3). Cross-head 42 carries horizontal bar 46, to which bar the sprockets 47 and 48 are rotatably secured. The ends 51 and 52 of chain 53 are anchored respectively to the ends of bar 46 (Figs. 3 and 10). Sprockets 54 and 55 are rotatably mounted on channel rail 14. From end 51 chain 53 passes (Fig. 3) over sprocket 54, thence over sprocket 47 and thence over sprocket 56 rotatably mounted on plate 27. The chain extends thence to and over sprocket 57 rotatably mounted on plate 27, thence over sprocket 48, thence over sprocket 55 to end 52 attached to the other end of bar 46. Shaft 32, by which offset roller 31 is carried, is provided (Fig. 8) with a rotatably fitting annulus 58 (the outer race of ball bearing 59). With cross-head 42 in mid-position with reference to the over-all stroke of piston 39, and with offset cylinder 31 in mid-position horizontally, the annulus 58 is secured to chain 53 by fitting 60 (Fig. 8). As a result of this construction, when piston 39 of air cylinder 40 moves in one direction, offset cylinder 31 is thereby propelled at twice the rate and for twice the distance in the opposite direction and vice versa. This operates to bring the offset cylinder 31 (Figs. 1 and 2) rapidly in succession over the impression plates 18, 19 and 20 and over the impression plates 21, 22 and 23 and thence to the end 35 (Figs. 1 and 2) of table 13, during which time the offset cylinder 31 is of course being rapidly and accurately turned by means of the cooperation of gears 33 and 34 with the racks 28 and 29.

In addition to the foregoing I preferably provide means for selectively applying the desired

colors of ink to the various impression plates 18-23. As illustrated in Fig. 1, this includes the rolls 61, 62 and 63, each divided longitudinally into three separate sections to prevent intermixing of the respective inks. Roll 62 is mounted on shaft 64 rotatably carried in suitable bearings, which shaft is splined to V-pulley 65 (Figs. 1 and 4). This pulley (Fig. 4) is directly driven through V-belt 66 by motor 67. Roll 61 is carried by shaft 71 which is rotatably and slidably mounted in suitable bearings (Figs. 1, 2 and 14). Roll 61 contacts and is driven by roll 62 (Fig. 14). Shaft 71 is splined (Figs. 1 and 12) to the eccentric 72 co-acting with stationary dog 73 so that as the roll 61 turns, it is also oscillated longitudinally to effect more efficient spreading of ink. Roll 63 is carried by shaft 74 which also is rotatably and slidably carried in suitable bearings. Shaft 74 is similarly splined (Figs. 1 and 12) to eccentric 75 co-acting with dog 76. Roll 63 contacts and is driven by roll 62 (Fig. 14) and in turning also oscillates longitudinally to effect more efficient spreading of the ink. Roll 63 is preferably of metal. The desired color ink is applied intermittently by hand to the corresponding section of the rolls and is worked up by the rolls into a continuous film covering uniformly that section of the surfaces of the rolls to which it is applied. Rolls 63 and 64 may therefore be designated as ink distributing rolls while roll 61 may be designated as an ink supplying roll since this is the roll which furnishes the ink to the inking roller 77 carried by shaft 78. This roller is correspondingly divided into three sections. Shaft 78 is carried in ball bearings 79 and 80, the outer races of which (Fig. 23) do not turn but carry rotatably the pulleys 81 and 82, which track respectively on transverse guide bars 84 and 85 (Figs. 1, 2 and 13). As a consequence of this construction, inking roller 77 rolls horizontally over the impression plates and on returning rolls down into contact with the ink supplying roll 61 by which the films of ink on roller 77 of the respective colors are renewed. The relative positions of the rolls and roller 77 at this stage appear in Fig. 14.

Preferably means is provided for automatically moving roller 77 over the impression plates and back into contact with the roll 61. This means (Figs. 3, 4 and 5) includes the single acting spring return air cylinder 85 pivotally mounted by the fitting 97 on floor 12 at its lower end operating piston 86 pivotally connected to crank 87 pinned to shaft 88. Shaft 88 is rotatably mounted in bearings suitably supported by table 13, the ends of shaft 88 being secured respectively to cranks 89 and 90 (Fig. 3). These cranks terminate at their upper end respectively in clevises 91 and 92 connected (Fig. 23) to links 93 and 94, the other ends of which are rigidly connected to the outer races of ball bearings 79 and 80. As a consequence of this construction the spring 101 normally holds piston 86 extended and in this position roller 77 is in the position indicated in Figs. 2 and 14, in which it is in rolling contact with, and is receiving a fresh supply of ink from, the surface of ink supplying roll 61. When, however, air is admitted to the cylinder 85, piston 86 is retracted, with the result that roller 77 moves in the direction indicated by arrow 102 (Fig. 1) to apply a fresh supply of ink to the surfaces of the impression plates.

I will now describe the mechanism by which the design picked up on offset roller 31 is transferred to the object to be printed. For this pur-

pose I provide (Figs. 2, 3, 15 and 16) bed 110 adjacent the end 35 of the apparatus. This bed is vertically adjustable to bring the axis of the object to be printed into the horizontal plane of the axis of the offset roller. To that end it is supported by angles 111 and 112 secured to vertical strips (two on either side), of which 113 and 114 appear in Fig. 15, by horizontal compression strips 115 locked in position by bolts 116 and 117 (Figs. 19 and 20). The vertical strips are secured (Figs. 4 and 15) at top and bottom respectively to channels 14 and 15 by angles 118. Bed 110 is provided with stationary rails 119 and 120. Platform 121 (Fig. 15) is provided with channels 122 and 123 cooperating respectively with rails 119 and 120 by which the platform is guided rectilinearly and may be moved back and forth in a direction parallel to the rails 119 and 120, which is also parallel to the direction of racks 28 and 29. Platform 121 carries the associated pair of upstanding arms 125 and 126. The arm 125 carries the rollers 127, 128, 129 and 130 (Fig. 18) and the arm 126 carries the rollers 131, 132 and 133 (Fig. 17). The number and location of the rollers will of course be changed to accommodate the size and form of the particular object being printed. In consequence of this construction, a bottle or other object to be printed may be easily and quickly placed in position between the upper ends of the arms 125 and 126 nesting in rollers 127-133 and will be held in this position, freely rotatable by any external force. A similar construction is provided between the companion upstanding arms 134 and 135. Platform 121 is continuously urged (Fig. 16) in the direction indicated by arrow 136 by tension springs 137 and 138 anchored to cross-bar 139 (Fig. 5). Stop 141 (Fig. 16) is provided to prevent the platform from moving beyond edge 142 of bed 110. Because of this construction, when transfer roller 31 is over the impression plates platform 121 has moved as far as possible in the direction indicated by arrow 136 and is in contact with stop 141. When, however, transfer roller 31 passes off of the impression plates in the reverse direction indicated by arrow 140 (Fig. 2) it contacts the objects to be printed and in its progressive rolling toward end 35 of table 13 imparts this rolling motion to the objects to be printed. This rolling motion of transfer roller 31 continues until the design has been completely transferred to, and impressed upon, the objects to be printed. This is made possible by the fact that platform 121 does not resist the rolling motion of offset roller 31 because it is entirely free to and does move freely in the direction indicated by arrow 140 (Fig. 2). After the transfer roller has completed this movement, it is automatically returned to and over the impression plates while platform 121, under the tension exerted by springs 137 and 138, moves automatically back to its original position in contact with stop 141. At this moment the operator removes the printed objects and replaces them with objects which have not yet been printed, whereupon the operation is repeated.

In a case where the object to be printed upon is of yielding construction, as for example, a deformable bottle or similar container made of thin-walled plastic material, I find it advisable to provide on platform 121 some means for limiting the pressure exerted between the object and the transfer roller. One way of accomplishing this purpose is to provide (Fig. 16) on platform 121 the upstanding arms 151 and 152 provided with rollers 153 and 154. These rollers are ad-

justable relative to the arms 125 and 126 and the rollers 127-132 carried thereby. This may be accomplished either by making arms 151 and 152 adjustable on platform 121 in the direction of movement of the platform, or alternatively by making arms 125 and 126 similarly adjustable. In the specific embodiment of my invention shown I have made the arms 125, 126, 134 and 135 adjustable so that the arms may be adjustably secured in position on platform 121. However made, the adjustment is such that when the offset roller 31 is in contact with the objects to be printed, the rollers 153 and 154 are also in contact with the offset roller to take up a part of the pressure transmitted to platform 121 and thereby prevent the application of undue force to the objects to be printed, which would deform the objects with the resultant smearing of the design.

For the purpose of operating the device in the desired sequence, I provide in addition the following equipment. The shaft 162 (Fig. 4) driven by motor 67 is provided with two V-pulleys. Pulley 163 (Fig. 4) drives V-belt 164 running over driven pulley 165 (Figs. 3, 4 and 5). The driven pulley 165 drives shaft 166 journaled in the upstanding flanges 167 and 168 (Fig. 3) carried by floor 12. Through coacting spur gears 171 and 172 it also drives reversely shaft 173 similarly journaled in the upstanding flanges 167 and 168. Shaft 166 carries two cams, 174 and 175 (Figs. 3, 21 and 22), co-acting with dual control air valve 176. The shaft 173 carries cams 177 and 178 also cooperating with air valve 174. Air valve 176 (Fig. 3) is connected to a supply of air under pressure from pipe 181 through T-connection 182 and is in turn connected to air cylinder 38 through tubes 183 and 184. By reason of this construction when these cams are in one position air cylinder 38 is receiving air under pressure at end 185 and discharging freely at end 186 to move the piston in one direction, and when the cams have turned through an angle of 180°, this operation is reversed, with the result that the cylinder is receiving air at the end 186 and discharging freely at the end 185. Thus the movement of driven pulley 165 through an angle of 360° operates to complete the cycle of movement of piston 39, thereby moving transfer roller 31 from the position indicated in Fig. 1 over the entire length of bed 17 and reversely back to this position.

The single acting air cylinder 85 is supplied with air through tube 188 from single acting air valve 189, with the result that when the transfer cylinder 31 has moved into printing contact with the objects to be printed and has therefore cleared bed 17, cam 192 (Figs. 3 and 22) operates valve 189 thereby introducing air under pressure to the end 193 of air cylinder 85, thereby retracting piston 86, with the result that inking roller 71 is moved from the position indicated in Fig. 2 over the impression plates. As soon as cam 192 releases the air valve 189 the contained air under pressure bleeds itself out of cylinder 85, with the result that piston 86 extends and inking roller 71 returns to the position shown in Fig. 2. In this position it does not interfere with the longitudinal movement of transfer roller 31 over bed 17 and the movement of roller 31 over the bed is timed to be completed while ink applying roller 71 is in the position shown in Fig. 2.

In actual practice the sequence of operations occurs with considerable rapidity and I find it possible with my apparatus to make about ten

printings per minute. In case two objects are printed simultaneously, as is possible with the construction shown in the drawings, this corresponds to the complete printing of twenty objects per minute. It will of course be understood that I may, if desired, provide for the simultaneous printing of more than two objects but this would require the services of more than one operator to remove and replace the objects being printed.

The foregoing description is for purposes of illustration and not of limitation and it is therefore my intention that the invention be limited only by the appended claims or their equivalents wherein I have endeavored to claim broadly all inherent novelty.

I claim:

1. In a machine for transfer printing on objects of roughly circular section concentric with a single axis including a bed plate, means for securing at least one impression plate to said bed plate, and a transfer roller, the improvement of means guiding said transfer roller rectilinearly over in rolling contact with and beyond such impression plate, means holding such an object freely rotatable about its axis with said axis parallel to the axis of said transfer roller, a horizontal platform carrying said means holding, horizontal channels carried by said platform, horizontal rails cooperating therewith fixed to said machine, said channels and rails being oriented in the direction of translation of said transfer roller, and means yieldingly urging said platform and said means holding carried thereby toward said transfer roller, whereby following initial contact between said object and said transfer roller the two continue in rolling contact and the image is transferred from said transfer roller to said object.

2. A machine according to claim 1 including also means limiting the pressure between said object and said transfer roller in rolling contact.

3. A machine according to claim 1 including also rollers carried by said platform adapted to make rolling contact with said transfer roller when said transfer roller is in rolling contact with said object and adjustable with respect to said means holding to limit the pressure between said object and said transfer roller in rolling contact.

4. In a machine for transfer printing on objects of roughly circular section concentric with a single axis including a bed plate, means for securing at least one impression plate to said bed plate, and a transfer roller, the improvement of means guiding said transfer roller rectilinearly over in rolling contact with and beyond such impression plate, means holding such an object freely rotatable about its axis with said axis parallel to the axis of said transfer roller, a horizontal platform carrying said means holding, horizontal channels carried by said platform, horizontal rails cooperating therewith fixed to said machine, said channels and rails being oriented in the direction of translation of said transfer roller, means yieldingly urging said platform and the means holding carried thereby toward said transfer roller and mechanical means moving said transfer roller over in rolling contact with such impression plate and beyond in rolling contact with said object.

5. A machine according to claim 4 including also means limiting the pressure between said object and said transfer roller in rolling contact.

6. A machine according to claim 4 including

also rollers carried by said platform adapted to make rolling contact with said transfer roller when said transfer roller is in rolling contact with said object and adjustable with respect to said means holding to limit the pressure between said object and said transfer roller in rolling contact.

7. In a machine for transfer printing on objects of roughly circular section concentric with a single axis including a bed plate, means for securing at least one impression plate to said bed plate and a transfer roller, the improvement of at least one rack, at least one spur gear co-axial with said transfer roller, said rack and gear guiding said transfer roller rectilinearly over in rolling contact with and beyond such impression plate, at least one track parallel to said rack, a platform slideable upon said track, means carried by said platform holding such an object freely rotatable about its axis with its axis parallel to the axis of said transfer roller, said platform being slideable upon said track with said object in rolling contact with said transfer roller and means yieldingly urging said platform toward said transfer roller.

8. A machine according to claim 7 including also rollers carried by said platform adapted to make rolling contact with said transfer roller when said transfer roller is in rolling contact with said object and adjustable with respect to said means holding to limit the pressure between said object and said transfer roller in rolling contact.

9. In a machine for transfer printing on objects of roughly circular section concentric with a single axis, including a bed plate, means for securing at least one impression plate to said bed plate, and a transfer roller, the improvement of at least one rack, at least one spur gear co-axial with said transfer roller, said rack and gear guiding said transfer roller rectilinearly over in rolling contact with and beyond such impression plate, at least one track parallel to said rack, a platform slideable upon said track, means carried by said platform holding such an object freely rotatable about its axis with its axis parallel to the axis of said transfer roller, said platform being slideable upon said track with said object in rolling contact with said transfer roller and mechanical means moving said transfer roller over in rolling contact with such impression plate and beyond in rolling contact with said object and means yieldingly urging said platform toward said transfer roller.

10. A machine according to claim 9 including also rollers carried by said platform adapted to make rolling contact with said transfer roller when said transfer roller is in rolling contact with said object and adjustable with respect to said means holding to limit the pressure between said object and said transfer roller in rolling contact.

11. In a machine for transfer printing on objects of roughly circular section concentric with a single axis, including a bed plate, means for securing at least one impression plate to said bed plate, a transfer roller, and means guiding said transfer roller rectilinearly over in rolling contact with said impression plate, the improvement of an ink distributing and an ink supplying roll parallel to said means guiding said transfer roller, an inking roller parallel to said ink supplying roll, means guiding said inking roller in a direction normal to the movement of said transfer roller, and mechanical means

moving said inking roller over said last mentioned guide means in rolling contact with such impression plate and back into rolling contact with said ink supplying roll.

12. A machine according to claim 11 in which said mechanical means comprises an air cylinder secured to said machine, a fitting carried by the piston of said air cylinder, two sprockets rotatably carried by said fitting, two sprockets secured to said machine, an open end chain, the ends of which are secured to said fitting running over said sprockets and rotatably secured to said transfer roller adjacent the middle thereof.

13. In a machine for transfer printing on objects of roughly circular section concentric with a single axis including a bed plate, means for securing at least one impression plate to said bed plate, and a transfer roller, the improvement of means guiding said transfer roller rectilinearly over in rolling contact with and beyond such impression plate, means holding such an object freely rotatable about its axis with said axis parallel to the axis of said transfer roller, a platform carrying said means holding, horizontal channels carried by said platform, horizontal rails cooperating therewith fixed to said machine, said channels and rails being oriented in said rectilinear direction, means yieldingly urging said platform and said means holding carried thereby toward said transfer roller, mechanical means moving said transfer roller over in rolling contact with such impression plate and beyond in rolling contact with said object, ink distributing and ink supplying rolls parallel to said means guiding said transfer roller, an inking roller parallel to said ink supplying roll, means guiding said inking roller in a direction normal to the movement of said transfer roller, and mechanical means moving said inking roller over said last mentioned guide means in rolling contact with such impression plate and back into rolling contact with said ink supplying roll.

14. A machine according to claim 13 including also means limiting the pressure between said object and said transfer roller in rolling contact.

15. In a machine for transfer printing on objects of roughly circular section concentric with a single axis including a bed plate, means for securing at least one impression plate to said bed plate, and a transfer roller, the improvement of at least one rack, at least one spur gear coaxial with said transfer roller, said rack and gear guiding said transfer roller rectilinearly over in rolling contact with and beyond such impression plate, at least one track parallel to said rack, a platform slidable upon said track, means carried by said platform holding such an object freely rotatable about its axis with its axis parallel to the axis of said transfer roller, said platform being slidable upon said track with said object in rolling contact with said transfer roller, means yieldingly urging said platform towards said transfer roller, an ink distributing and an ink supplying roll parallel to said rack, an inking roller parallel to said ink supplying roll, means guiding said inking roller in a direction normal to the movement of said transfer roller and mechanical means moving said inking roller over said last mentioned guide means in rolling contact with such impression plate and back into rolling contact with said ink supplying roller.

16. A machine according to claim 15 including also rollers carried by said platform adapted to make rolling contact with said transfer roller when said transfer roller is in rolling contact with said object and adjustable with respect to said means holding to limit the pressure between said object and said transfer roller in rolling contact.
